UNITED STATES PATENT OFFICE.

JAMES R. MAHONEY, OF PITTSBURGH, PENNSYLVANIA, ASSIGNOR TO MRS. HARRY S. DALY, OF PITTSBURGH, PENNSYLVANIA.

DESIGN FOR A TEACUP OR SIMILAR ARTICLE OF MANUFACTURE.

Application filed February 5, 1926. Serial No. 16,409. Term of patent 7 years.

To all whom it may concern:

Be it known that I, JAMES R. MAHONEY, a citizen of the United States, residing at Pittsburgh, in the county of Allegheny and State of Pennsylvania, have invented a new, original, and ornamental Design for a Teacup or Similar Article of Manufacture, of which the following is a specification, reference being had to the accompanying drawing, forming part thereof.

What I claim is:

The ornamental design for a teacup or similar article of manufacture substantially as shown and described.

JAMES R. MAHONEY.
